LAMINATED SHEET PULP CONTAINER AND METHOD OF FORMING SAME

Lee M. Wiley, Marion, Ind., assignor of one-third
to Julian T. Lett and one-third to Reeley B.
Wiley

Application December 3, 1942, Serial No. 467,715

1 Claim. (Cl. 154—2)

This invention relates to a deep drawn seam-
less container formed primarily of sheet pulp
stock.

The present invention also is directed to the
means for and method of laminating such stock
to produce a composite, laminated sheet prior
to formation therefrom of the aforesaid con-
tainer.

The laminated sheet comprises the stock which
is first passed through impregnating tanks, and
then through a wringer structure to form a mois-
tened, impregnated loop which is then fed to
blanking dies to form blanks. These blanks are
then precreased and drawn through tubular die
extensions by plungers that subsequently eject
the partially formed article into a receiver mold
wherein the container side wall precreased stock
is consolidated and distributed by the plunger
to form an article that approximates final form.

The receiver molds are turret mounted and
successively presented in indexed turret rota-
tion to successive pressure stations and a final
discharge station. Here the articles are suit-
ably transferred to a conveyor for transportation
to and through a heater.

This heater evaporates the remaining mois-
ture not mechanically extruded from the art-
icle. These articles are then pressure formed
and in oversize relation and then shrunk to size
in a second heater that operates at a temperature
high enough to cause dispersion and distribution
of the residual impregnate or size. Final pressure
forming and decorating then may be effected if
desired.

An alternate method or processing is for the
conveyor supported, turret mold ejected articles
to pass through a unitary two stage heater, in
the first stage (of longer duration) being sub-
jected to drying and in the second stage (shorter
duration) being subjected to further drying but
at a higher temperature sufficient to thermally
condition the article carried impregnate or size,
so that it can be consolidated in a final pressure
formation.

The latter may occur in a turret type mecha-
nism, there being included between the receiv-
ing molds of the same and the conveyor beyond
the heater, a suitable stripper. The turret die
consolidated and formed article may then be
printed, decorated or the like, as desired, and
finally ejected.

Illustrative of apparatus and methods for prac-
ticing parts of the present invention reference
may be had to the following copending patents:
No. 2,337,581, dated Dec. 28, 1943; No. 2,348,871,

dated May 16, 1944; No. 2,348,272, dated May 9,
1944; No. 2,296,889, dated Sept. 29, 1942; No.
2,354,564, dated July 25, 1944; and allowed ap-
plication Serial No. 444,671, now Patent No.
2,377,392, dated June 5, 1945.

Since these patents are readily available for a
detailed disclosure of complete article formation,
and since the résumé hereinbefore briefly sum-
marizes said disclosures, no further reference
thereto is believed necessary if it be distinctly
understood that the present disclosure is directed
to laminated sheet formation for laminated art-
icle formation.

The subsequent disclosure is confined, to min-
imize descriptive matter only. However, it is
amplified by a disclosure of the article, or rather
parts and sections thereof when including the
laminated sheet pulp stock of this invention.

The chief object of this invention is to provide
a laminated pulp sheet including outer layers or
plies of sheet pulp and an intermediate layer or
ply of plastic for reenforcement purposes, for her-
metic sealing purposes, and for non-tacky han-
dling of the subsequent laminated sheet in the
several processes and apparatuses summarized
hereinbefore and also illustrated and described in
said patents.

The chief feature of the present invention con-
sists in the utilization, when desired, of tacky
plastic, water repellent and/or thermal and/or
pressure setting in character.

Other objects and features of this invention
will be set forth more fully hereinafter.

The full nature of the invention will be under-
stood from the accompanying drawings and the
following description and claim:

In the drawings,

Fig. 1 is a diagrammatic elevation outline of the
prelaminating formation of a laminated paper
board pulp sheet including the inclusion of a
sheet of plastic for laminating purposes.

Fig. 2 is a similar view of a modified form of
the invention and represents plastic lamination
inclusion when the plastic is in liquid form.

Fig. 3 is a similar view of a further modified
form of the invention and when the plastic lamination
inclusion is initially in powder form.

Fig. 4 is a top plan view of an article including
the laminated sheet and prior to final consolida-
tion steps disclosed in the copending applica-
tions.

Fig. 5 is a similar view on an enlarged scale
of a small section thereof.

Fig. 6 is a view similar to Fig. 5 and with the

parts of the article in final wall consolidated relation.

Fig. 7 is a vertical sectional view taken on line 1-1 of Fig. 4 and in the direction of the arrows and on a scale approximately four times Fig. 4 scale, which may, for illustration purposes, be considered substantially full size.

Fig. 8A is a longitudinal sectional view of one apparatus illustrating the blanking, pre-creasing, creasing and initial formation of the article.

Fig. 8B is a similar view of the dehydrator through which the article passes.

Fig. 8C is a similar view of an intermediate forming press and a second oven through which the article passes.

Fig. 9 is a face view of the movable pre-creasing die shown in Fig. 8A.

Fig. 10 is a face view of the stationary pre-creasing corrugated and tubular die shown in Fig. 8A.

Figs. 11a, 11b and 11c are sectional views showing successive relative positions of the movable pre-creasing die and stationary pre-creasing die, immediately prior to pre-creasing, intermediate pre-creasing and final pre-creasing of the blank.

Fig. 12 is a side elevation of a modified form of apparatus to which the conveyor shown in Fig. 8A may connect and which may replace the apparatus shown in Figs. 8B and 8C and is distinguished by an oven with superposed communicating chambers of dehydrating and presetting character and a turret type final former.

In each of the Figs. 1 to 3, 10 indicates a roll support and 11 a second roll support, the former supporting a roll 12 of prime pulp sheeting (bleached or unbleached) and the latter supporting a similar roll 13. From the same are drawn the sheets 14 and 15 respectively.

Following suitable plastic inclusion therebetween, as hereinafter more fully set forth, the resulting laminated sheet 16 passes into an impregnating tank 17 below an impregnating solution immersed roll 18 suitably suspended in the tank as at 19. The sheet then passes below roll 20 similarly suspended as at 21 and thence passes upwardly between wringer rolls 22.

The impregnating solution in the tank 17 is of the desired character, but is intended primarily for surface treatment of the finished article.

The sheet 16 extends upwardly from the wringer rolls 22 and passes over an elevated support roll 23 supported as at 24. A gravity retained light roll 25 with shaft 26 seated in slots 27 of support 24 overlies and bears on the sheet 16.

The sheet 16 leaving rolls 23-25 forms a loop or festoon 28 and the other end thereof passes over roll 29 of the block diagrammed forming machine 30, see Figs. 1 to 3. Herein one or more impregnating tanks 17 and associated mechanism may be utilized as desired or required.

Reference will now be had to Fig. 1 herein. Between rolls 12 and 13 and upon a roll support 40 there is supported a roll 41 of plastic in sheet form. A separating sheet of non-adhering material such as holland cloth may be included when necessary, but is stripped as the roll is stripped leaving only the plastic sheet 42. The separating strip disclosure is omitted for clarity as well as any rewind structure therefor if utilized.

The water repellant, normally non-tacky flexible sheet 42 is then subjected to a suitable solvent spray 43 obtained by passing the sheet between oppositely directed solvent discharging spray nozzles 44. This solvent tempers the plastic sheet 42 surfaces so same will adhere to the

pulp sheets 14 and 15 when presented thereto. This occurs at or immediately prior to the sheets passing through the booster and squeezing rolls 45 adjacent tank 17.

In passing through these rolls, or a similar pressure roll set ahead of same, the three sheets are caused to adhere together. The plastic layer being water repellent thus prevents water passage through the laminated sheet. Since the plastic ply is flexible, it will conform with the two outer plies of the sheet to whatever deformation the laminated sheet is thereafter subjected.

Reference will now be had to Fig. 2. In this disclosure the plastic intermediate ply initially is of liquid character, being contained in a tank 50, the same being automatically or manually supplied with the liquid and the temperature of which may be automatically or manually controlled if necessary.

In said tank 50 is a doctor roll 51 for transferring the liquid to the application roll 52 over which passes the sheet 14. Sheet 15 passes over roll 53 and engages the plastic covered lower face of sheet 14. Upper squeeze roll 54 cooperates with lower roll 53 to cause adherence of the now plastic inner layer to both liner plies. The resultant is a laminated pulp sheet similar to that previously described.

In Fig. 3 a third method of plastic lamination application is illustrated. Herein the plastic is in powder form. The two sheets 14 and 15 pass between booster rolls 60 and then into tank 61 through inlet 61a. It then passes below roll 62 in the tank and out through outlet 61b. This tank contains vapor for softening the two sheets. Steam supply lines, etc., 63 are provided.

The softened sheets then pass between squeeze rolls 64 and surplus softening material, if condensed, is squeezed out and runs back on the sheets and into the tank. The sheets, after passing between the squeeze rolls 64, separate and the lower sheet (ply 15) passes over approach roller 65 and platen 66. The upper sheet passes over overhead roller 67 and 68.

Between the two sheets is a supply container 69 containing powdered plastic. The discharge therefrom may be regulated in the throat 70. The powder P drops or is forced under pressure onto the upper face of sheet 15, while on the platen 66. A gauge 71, of adjustable character, determines the thickness of the powder layer. This gauge may be of scraper type.

A pair of squeeze rolls 72 and 73 are positioned adjacent the discharge end of the platen 66. Sheet 14 passing over roll 68 passes under roll 72. Sheet 15, covered with powdered plastic to the desired depth, passes directly from the platen to roller 73. The two sheets with the included powdered plastic are then consolidated in their passage through rolls 72-73 into a laminated sheet similar to each of the aforesaid sheets.

As previously stated, each of the laminated sheets 16 then passes between booster and squeeze rolls 45 and then through tank 17 and wringer 22-22 forming loop 28 prior to introduction to the forming machine 30.

Reference will now be had to Figs. 4 to 7 inclusive. The composite sheet as stated is initially blanked, see left-hand portion of Fig. 8A, and the blanks precreased, see same portion of Figs. 8A, 11a, 11b and 11c then drawn through a die, see Figs. 8A and 10, and seated in a female mold, see Fig. 8A, and pressure molded to approximate form (see central portion of Fig. 8A).

Figs. 8B and 8C disclose respectively a dehy-

drator and a forming press and second oven. The movable precreasing die is illustrated in Fig. 9 as well as Fig. 8A. Fig. 12 illustrates an alternative composite dehydrating and tempering oven and another form of final finishing press, same being of the turret type.

Fig. 8A corresponds to Fig. 1 of Patent No. 2,348,272.

Fig. 8B corresponds to Fig. 2 thereof and Fig. 8C corresponds to Fig. 3 thereof.

Figs. 9 and 10 correspond to Figs. 9 and 10 of Patent No. 2,337,581.

Figs. 11a, 11b and 11c correspond respectively to Figs. 12, 13 and 14 of the aforesaid last mentioned patent.

Fig. 12 corresponds to Fig. 1 of Patent No. 2,377,392.

In Figs. 4 and 7, 80 indicates the bottom of the article initially formed, 81 the sidewall portion immediately contiguous thereto, 82 indicates the initially pleated portion and 83 the upper fully pleated portion. Fig. 5 illustrates the upper fully pleated portion 83 prior to full consolidation. Each pleat in cross section is substantially U-shaped with inturned arm portions, see Fig. 5.

The successive pleats are reversed in position and are continuations of each other. When the pleats are finally consolidated, see Fig. 6, the interior and exterior surfaces of the container or article are of continuous wood pulp type. The plastic layer is therebetween and also pleated. This obviously constitutes a stiff ribbed reinforcement for the container sidewall. No external or internal ribbing or creases appear in the finished product. The pulp sheets due to impregnation have the desired finish.

The intermediate layer of plastic or ribbed reinforcement between the pulp sheets, so far as the side wall is concerned, adds considerable strength to the molded container over one of the same wall thickness, but made of a single pulp sheet, or a plurality of pulp sheets. The present invention forms a homogeneous wall between the two fibre walls so that hermetically sealed packaging can be accomplished where pulp only might fail.

It will also be apparent that by laminating in any of the manners illustrated and described practically any thermoplastic material can be used for the laminated board due to the fact that at no time in any of the article formation steps does such plastic material contact the male or female mold. This permits use of extremely tacky plastics when desired or required.

Due to the plastic separation between the sheets 85 either or both may be treated for water re-

pellency, heat resistance and the like and by surface treatment only. Different colored sheets also may be employed with the present invention, so that either interior or exterior or both can be of the desired color or colors.

The critical feature of the present invention is the formation of a multiply sheet with an included plastic bond between adjacent pulp sheets and coextensive therewith, the plastic being homogeneously united to the confronting surfaces of the plastic bonded sheets.

Desirable characteristics are strengthening of the article, possible hermetical sealing of the article, subsequent formation, without difficulties enumerated, of multi-ply blanks into containers.

While the invention has been illustrated and described in great detail in the drawings and foregoing description, the same is to be considered as illustrative and not restrictive in character.

The several modifications described herein, as well as others which will readily suggest themselves to persons skilled in this art, all are considered to be within the broad scope of the invention, reference being had to the appended claim.

The invention claimed is:

A method of forming a deep drawn, seamless, laminated wall container of substantially uniform wall thickness in transverse section and with an inner surface forming pulp layer, an outer surface forming pulp layer and an intermediate imperforate plastic layer therebetween comprising initially assembling two water and size absorbing pulp plies with a water repellent, temperature and pressure settable bonding plastic layer therebetween and coextensive therewith, consolidating by pressure the plies and layer into a unitary laminated sheet, impregnating the pulp plies of the sheet with moisture, the impregnation being with or without size as desired, wringing the sheet to the desired moisture content for subsequent working of the sheet in blank form such as initially precreasing the blank and then forming side wall flutes or pleats in the blank in registration with the creasing, compressing, consolidating and distributing the fluted material to form an article with an imbedded imperforate plastic reinforcement of concentric circumferential and radial type in the wall, and of approximately final form, pressure consolidating the article to nearly final form, subjecting the article to successive heatings for drying and setting purposes, and finally pressure finishing the article to final container form.

LEE M. WILEY.
